United States Patent

Des. 237,235
Patented Oct. 21, 1975

237,235

CABINET OR SIMILAR ARTICLE

John D. Iacurto, Pittsburgh, and Marvin S. Levine,
Monroeville, Pa., assignors to United States Steel
Corporation

Filed Dec. 15, 1972, Ser. No. 315,743

Term of patent 14 years

Int. Cl. D6—03

U.S. Cl. D6—167

FIG. 1

FIG. 2

FIG. 3

FIG. 1 is a front elevation, partly in section, of a cabinet embodying our design;

FIG. 2 is a bottom view of said cabinet, partially broken away; and

FIG. 3 is an isometric view of said cabinet.

The side of the cabinet not shown is like the side shown while the back is plain and unornamented.

We claim:

The ornamental design for a cabinet or similar article, as shown and described.
